CLAIM

The ornamental design for a shade canopy, as shown and described.

DESCRIPTION

FIG. 1 is a first perspective view of a shade canopy showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is the using state of the shade canopy thereof;

FIG. 10 is an enlarged view of the selected portion 10 in FIG. 2; and,

FIG. 11 is an enlarged view of the selected portion 11 in FIG. 2.

The broken lines shown in the drawings depict portions of the shade canopy that form no part of the claimed design.

1 Claim, 11 Drawing Sheets
